UNITED STATES PATENT OFFICE

105,361

DESIGN FOR A SHOE POLISHER

William L. Connor, Los Angeles, Calif.

Application September 14, 1936, Serial No. 64,840

Term of patent 14 years

To all whom it may concern:

Be it known that I, William L. Connor, a citizen of the United States, residing at Los Angeles, in the county of Los Angeles, State of California, have invented a new, original, and ornamental Design for a Shoe Polisher, of which the following is a specification, reference being had to the accompanying drawing, forming part thereof, in which:

Fig. 1 is a side elevational view of a shoe polisher showing my new design;

Fig. 2 is a perspective view looking toward the rear end thereof;

Fig. 3 is a perspective view looking toward the forward end thereof; and

Fig. 4 is a rear elevation.

I claim:

The ornamental design for a shoe polisher substantially as shown.

WILLIAM L. CONNOR.
